UNITED STATES PATENT OFFICE.

WILLIAM HOOKER ATWOOD, OF NEW HAVEN, CONNECTICUT.

DESIGN FOR AN AUTOMOBILE-BODY.

SPECIFICATION forming part of Design No. 31,690, dated October 17, 1899.

Application filed September 20, 1899. Serial No. 731,126. Term of patent 14 years.

To all whom it may concern:

Be it known that I, WILLIAM HOOKER ATWOOD, a citizen of the United States, residing in the city of New Haven, county of New Haven, State of Connecticut, have invented and produced a certain new and original Design for Automobile-Bodies, of which the following is a specification, reference being had to the accompanying drawings, forming a part

thereof.

This invention relates to bodies for automobiles or motor road-vehicles; and it consists in the design therefor shown in the accompanying drawings, in which—

15 Figures 1 and 2 are respectively a side view and a front perspective of a body for an automobile or motor road-vehicle which embodies the design.

The design presents in appearance a forward or main body portion A and a rear body portion B. The main or forward body portion is defined by a curved line from a to a' like the arc of a circle, a generally horizontal but slightly-curved line from a to a², and a

25 line curved on a relatively smaller radius

than the first line from a' to a², where it is merged in the line a a². The rear body portion B, when seen also in side elevation, is a generally quadrangular figure subordinate to and in harmony with the main body portion. 30 A compound curved line, as from c to c', carries the eye easily from the curved line a a', with which it conforms closely for a portion of its length.

The characteristic features of the design 35 are the main body portion defined by three lines, as described, and the generally quadrangular body portion in harmony with the main body portion, with a sweeping curved line connecting the two body portions and 40 unifying the whole design.

I claim as my invention—

The design for an automobile-body, substantially as shown and described.

This specification signed and witnessed this 45 18th day of September, A. D. 1899.

WILLIAM HOOKER ATWOOD.

In presence of—

HERMANN F. CUNTZ,
MAUD L. CLARK.
